Patented Feb. 15, 1921.

UNITED STATES PATENT OFFICE.

FRANK WILLIAMS, OF ST. LOUIS, MISSOURI, ASSIGNOR OF ONE-FOURTH TO FRED LUTGERS AND ONE-HALF TO LOUIS BURNIS, BOTH OF ST. LOUIS, MISSOURI.

NAIL-PULLER.

1,368,311.

Specification of Letters Patent. Patented Feb. 15, 1921.

Application filed April 14, 1920. Serial No. 373,892.

To all whom it may concern:

Be it known that I, FRANK WILLIAMS, a citizen of the United States, residing at St. Louis, in the State of Missouri, have invented a new and useful Nail-Puller, of which the following is a specification.

This invention relates to a nail puller or extractor and has for an object the provision of means for readily gripping the head of a driven or partly driven nail, and means for readily withdrawing the nail from the material in which it has been driven.

A further object of this invention is to provide a nail or spike extractor of generally improved construction whereby the device will be simple, durable and inexpensive in construction as well as convenient, practical efficient and serviceable in its use.

With the above and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

The invention has been illustrated in its preferred embodiments in the accompanying drawings; wherein—

Figure 1 is a side elevational view of the device;

Fig. 2 is a view taken at an angle of ninety degrees with respect to Fig. 1;

Fig. 3 is a longitudinal section view of the device;

Fig. 4 is a transverse sectional view taken on the line 4—4 of Fig. 1.

Fig. 5 is a fragmental longitudinal sectional view, showing the device in position to extract a partly drawn nail.

Referring to the drawings there is shown a casing comprising a tubular member 10 having a laterally extending enlargement 11 formed intermediate its ends. A rod or stem 12 is mounted for longitudinal sliding movement within the tubular member 10, and rack teeth 13 are formed along the longitudinal edge of the stem 12. These teeth 13 mesh with the teeth of a pinion 14 formed on a transversely extending shaft 15 which is mounted for rotation within a transversely disposed cylindrical recess 16

formed within the enlargement 11. The pinion 14 and shaft 15 are held against longitudinal or axial movement with respect to the cylindrical recess 16, by means of a screw or securing device 17 which extends through an aperture 18 formed in the enlargement 11 and is threaded into the shaft as shown at 19, and the enlarged head 20 of the screw engages the outer face of the enlargement 11. A transversely extending aperture 21 is formed adjacent the outer terminal of the shaft 15 for the reception of a manipulating handle or lever 22.

One terminal of the stem 12 is curved or turned upon itself, as indicated at 23, and it is then flattened and bifurcated to provide a claw 24. The opposed terminal of the stem is reduced to provide an attaching lug 25 to which opposing gripping jaws 26 are pivotally secured as shown at 27. Each jaw 26 includes an attaching ear 28, from which point the jaw is laterally tapered as indicated at 29, and the outer terminal of the jaw is provided with an undercut claw 30. The tapered or inclined surface 29 is so disposed that the greatest transverse dimension of each jaw is found at a point adjacent the claw 30, or at a point remote from the pivot or securing point 27. Each attaching ear 28 is reduced in dimension to render them flexible so that the jaws 26 are normally spaced apart, but may readily yield to a closed or gripping position. The adjacent longitudinal edges of the jaws 26 are provided with opposed slots of kerfs 31 which are adapted to receive the head of a partly driven nail in order to entirely extract them. That terminal of the tubular member which is disposed adjacent the jaws 26 has its inner wall flared or tapered, as shown at 32 to coöperate with the inclined or tapered portions of the jaws 26 in order to move them to their closed or gripping position.

Diametrically opposed legs or supporting members 33 extending longitudinally from that terminal of the tubular member 10 which is disposed adjacent the jaw 26, and these legs 33 are adapted to engage the material from which the nail is to be withdrawn.

In operation, the jaws 26 are placed adjacent the head of the nail so that the claws 30 will engage the head. Then the entire casing is moved toward the jaws 26 until the

flared end 32 of the tubular member 10 engages the tapered surfaces 29 of the jaw 26, and further movement of the tubular member 10 in this direction will cause the jaws 26 to be moved toward each other and securely grip the nail. Now the outer ends of the supporting legs 33 engage the surfaces of the material from which the nail is to be withdrawn and by simply rotating 10 the shaft 15 by, means of the lever 22, the stem is moved away from the material in which the nail is driven and continued rotation of the shaft 15 and pinion 14 will entirely extract the nail. In structures where 15 partly drawn or protruding nail are formed, the protruding head of the nail may be readily gripped in the kerfs 31, as shown in Fig. 5 and then the nail may be entirely extracted. Relatively large nails or spikes 20 may be readily extracted by employing the claw 24. It will be observed that by forming the jaws 26 so that their greatest transverse or lateral dimension is located adjacent the claws 30 and remote from the attaching ears 25 28, that the engagement of the flared end 32 of the tubular members 10 with the inclined surface 29 will exert the greatest gripping force to the jaw at a point adjacent the claws 30. This arrangement causes the claws 30 to be forced under the head of the nail and at the same time causes only a minimum pressure to be imparted to the attaching ears 28.

Having thus described my device what is 35 claimed is:

1. A device of the class described including a tubular member having its inner wall

flared at one terminal thereof, a stem slidably mounted within the tubular member, opposed gripping jaws, resilient attaching 40 ears formed on the said jaws and secured to the said stem, tapered rigid portions formed on the jaws and extending outwardly from the resilient attaching ears, undercut claws formed at the outer terminals of the rigid 45 portions of the jaws, the rigid portions of the jaws having their greatest transverse dimension located at a point immediately adjacent the said claws and adapted to engage the flared terminal of the tubular member 50 to impart a gripping action to the said claws.

2. A device of the class described including a tubular member, a laterally extending enlargement formed on the tubular member, 55 said enlargement having a cylindrical recess which is transversely disposed with respect to the tubular member, a stem slidably mounted within the tubular member, rack teeth formed on the stem, gripping jaws 60 carried by the stem, a shaft rotatably mounted within the recess, said shaft having teeth formed thereon and adapted to mesh with the teeth formed on the stem, means for securing the shaft against longitudinal movement within the said recess, and a manipulating handle secured to the said shaft.

In testimony that I claim the foregoing as my own, I have hereto affixed my signature in the presence of two witnesses.

FRANK WILLIAMS.
